UNITED STATES PATENT OFFICE.

JAMES THIERRY, OF DETROIT, MICHIGAN.

REGULATING THE EXHAUST OF STEAM-ENGINES.

Specification of Letters Patent No. 28,918, dated June 26, 1860.

To all whom it may concern:

Be it known that I, JAMES THIERRY, of Detroit, in the county of Wayne, in the State of Michigan, have invented a new and useful Governor to regulate the Generating of Steam for Locomotive and other Engines Employing Steam-Blasts; and I do hereby declare that the following is a full and exact description thereof, reference being had to the accompanying drawings, and to letters of reference marked thereon.

The nature of my invention may be divided into two somewhat different combinations, which are as follows:

15 *Combination No. 1.*—In this arrangement I combine the exhaust-nozzle of a locomotive, or other steam-blast-employing engine, with a steam-balanced exhaust valve controlled by the variable pressure of the steam 20 in the boiler through the medium of an elastic siphon shaped steam tube or its equivalent, the opening of which exhaust-valve varying with the pressure in the boiler, thereby conducting-off variable quantities 25 of the exhaust-steam, otherwise passing through said nozzle, so as to vary the intensity of the steam-blast and conform the generating of the steam to the consumption of the same. Thus combined and applied my 30 invention becomes a governor to regulate the generating of steam, operated by the variable pressure of the steam in the boiler.

35 *Combination No. 2.*—This combination is like No. 1 with the following exceptions: The elastic siphon shaped steam tube and its steam-connections are omitted and substituted by some suitable hand-gear (such as a light iron rod reaching from the engine-man to a lever connected onto said exhaust-valve, 40 the controlling power of the steam being substituted by that of the engineman. In this case my invention becomes a governor to regulate the generating of steam, operated by the engineman through the medium of a 45 hand-gear.

To enable others skilled in the art to make and use my invention, I will proceed to describe its construction and operation.

50 *Construction and operation of combination No. 1.*—I construct my exhaust-pipe and nozzle in the usual forms, but in order to remove the injurious mode of regulating the production of steam by the use of a damper, or the alternate opening and closing of the furnace-door, I combine the exhaust-nozzle D (as shown in the accompany-

ing drawing) with a steam-balanced exhaust-valve C itself connected onto an elastic siphon-shaped steam tube R, which siphon-shaped steam tube being applied to the 60 boiler, either directly or through the medium of a steam-tube E, will be constantly filled with steam or water from said boiler, it follows as a consequence that the internal pressure of said siphon-tube will vary with that 65 in the boiler, distending said siphon-shaped steam-tube more or less according to the intensity of said pressure.

Before proceeding any further it is necessary to describe the exhaust-valve C which is 70 represented as a hollow-cylinder with a perforated bottom, fitting loosely into a cylindrical casing provided with exhaust-holes and tight bottom to prevent the escape of exhaust-steam in that direction. From the nature 75 of the functions of said exhaust valve it is clear that none but exhaust-steam can gain admission into its interior, the pressure of which steam constantly balancing itself on the surface of said valve will not affect the 80 same, and will therefore leave it perfectly free to follow the motion of the vibrating end of the siphon-tube to which it is attached.

85 *Mode of operation.*—A gradual increase of pressure in the boiler will occasion a gradual distention of the elastic siphon-shaped steam tube, which in its turn will gradually remove the exhaust-valve from its former 90 position to a point allowing just the required opening of valve to conduct off the exact portion of exhaust-steam (otherwise passing through the nozzle) exceeding the amount required through the nozzle to conform the intensity of the steam-blast, or the 95 generating of the steam to the consumption of the same. A decrease of pressure in the boiler, will relieve in part the siphon-shaped steam tube, thereby decreasing the 100 opening of said exhaust valve and at the same time increasing the amount of steam passing through said exhaust nozzle, which 105 will increase the intensity of the steam-blast and the amount of steam generating until it shall have reached the pressure in the boiler allowed by the regulating apparatus as described.

110 *Construction and operation of combination No. 2.*—In this arrangement the siphon-shaped steam tube R is not wanted and is therefore omitted, and a convenient hand-gear substituted in its place, which may be

applied as represented in Fig. 6, or in some other suitable manner. It is at once perceived that in this combination the regulation of the steam-balanced exhaust-valve C, 5 is entirely done by the engineman through the hand-gear, which he does by pulling or pushing the rod F as the engine may require.

What I claim as my invention and desire to secure by Letters Patent is as follows:

10 1. The combination of the exhaust-nozzle or nozzles of locomotive or other steam-blast employing engines, with a steam-balanced exhaust-valve controlled by the variable pressure of the steam in the boiler, through 15 the medium of an elastic siphon-shaped

steam-tube, or its equivalent; said combination producing a governor to regulate the generating of steam for said engines, substantially as above described.

2. The combination of said nozzle or nozzles with said balanced exhaust-valve controlled by the engineman through the medium of a convenient hand-gear, in substance and for the purpose as above described. 20

JAMES THIERRY.

In presence of—

JOHN C. WELLS,
MARCUS A. CHASE.
